[57] CLAIM

The ornamental design for a facsimile transceiver, as shown and described.

DESCRIPTION

FIG. 1 is a right side, top and front perspective view of a facsimile transceiver showing our new design.

FIG. 2 is a top plan view thereof;

FIG. 3 is a front elevational view thereof;

FIG. 4 is a left side view thereof;

FIG. 5 is a right side view thereof;

FIG. 6 is a rear elevational view thereof;

FIG. 7 is a bottom plan view thereof;

FIG. 8 is a right side, top and front perspective view of a facsimile transceiver showing another embodiment of my new design;

FIG. 9 is a top plan view thereof;

FIG. 10 is a front elevational view thereof;

FIG. 11 is a left side view thereof;

FIG. 12 is a right side view thereof;

FIG. 13 is a rear elevational view thereof;

FIG. 14 is a bottom plan view thereof;
